UNITED STATES PATENT OFFICE.

JACOB A. HYLE, OF ST. LOUIS, MISSOURI, AND MARK FRANKS, OF CHICAGO, ILLINOIS,
ASSIGNORS TO CONTINENTAL RAILWAY SUPPLY CORPORATION, A CORPORATION
OF DELAWARE.

RAIL ANCHOR FOR RAILWAYS.

Application filed April 13, 1926. Serial No. 101,637.

This invention pertains to novel improvements in one-piece rail anchors or anticreepers especially designed to be secured to the base portion of railroad track rails and in engagement with stationary parts of the road bed for the purpose of preventing longitudinal displacement of the rails during the travel of the rolling stock thereover.

The main object of the invention is to provide a novel, simple, economical, durable, practical and thoroughly efficient anchor from a single piece of high grade spring steel possessing maximum strength, which may be readily applied to the base of a track rail and securely retained in its proper operative position thereon, and which will always effectively grip the rail and cooperate with a stationary part of the road bed to prevent the track rail from creeping.

Another object of the invention is to so construct our improved device that it will always maintain an extremely effective and a firm frictional engagement with the track rail under all conditions of service.

Further objects of this invention are to so construct the novel rail anchoring device that it will successfully resist creeping of the track rail; that it may be removed and reapplied any number of times and always retain its effective tension and gripping power; that it furnishes the required bearing surface against the railroad tie and extends downwardly into the road ballast, and is so shaped at the point where it projects into the ballast that the vibration and wave motion of the rail will push the ballast apart so that it will not be in constant contact with said ballast thereby preventing interference with the railway electric signaling systems now employed.

The foregoing and such other objects as may appear from the ensuing description are accomplished by the construction, arrangement, location and combination of the parts hereinafter more fully described, illustrated in the accompanying drawings, and particularly pointed out in the claims appended hereto, it being understood that slight changes in the precise form, proportions and minor details of construction may be resorted to without departing from the spirit or sacrificing any of the advantages of the invention.

In the accompanying drawings forming a part of this specification it will be seen that:

Figure 1 is a side elevation of our improved device applied to a track rail, showing the track rail in cross-section and in side elevation a railway tie broken away.

Figure 2 is a perspective of the device detached from the rail, and

Figure 3 is an end elevation thereof.

In the embodiment of our invention as illustrated, the numeral 1 indicates a railroad track rail and 2 an underlying cross-tie forming a stationary part of the road bed and supporting the rail 1, the said rail having a tendency to creep, when subjected to the travel of the rolling stock thereover.

Our novel rail anchor 3 is formed from a single piece or flat bar of high carbon spring steel of the desired or required length, and may be of any desired thickness or width, preferably about one and a half inches wide and from one fourth to five sixteenths of an inch thick, one end portion, that is, the headed or jaw portion 4 being bent upon itself or doubled in the manner such as is clearly shown in Figs. 1 and 2, in order to furnish maximum strength with a minimum amount of steel, and said anchor may be formed by a suitable bending machine or drop forged.

The body portion of the anchor is formed with a downwardly extending V-shaped portion 5 adapted to rest and provide the desired bearing surface against the railway cross-tie 2, while its free outer end terminates with an upward extension 6 which is adapted to firmly and tightly grip one edge of the rail base, as shown in Fig. 1, and an opening 7 is formed therethrough for the purpose hereinafter described.

It will be perceived that this anchor is formed in such shape that the outer free end thereof normally extends in a horizontal plane above the level of the base portion 8 of the headed portion or jaw 4, so that when the anchor is adjusted to the track rail there will be continuous or constant high pressure upwardly by the end 6 against the lower surface of the rail, hence when a blow is struck against the outer face 9 of the V-shaped portion 5, or when a suitable tool is applied to the opening 7 the said outer end

portion 6 will be caused to immediately snap upwardly and tightly clamp the edge of the rail base, and is maintained in such position owing to the high tension or pressure exerted by the special and particular construction of said anchor, and owing to the continuous upward pressure of its outer end portion there is no possibility of the anchor loosening or dropping off, from the excessive 10 vibration which usually occurs during the passage of the rolling stock over the track rails.

In applying the anchor 3 to the rail 1, the anchor is first placed in its proper position with relation to the rail with the inner end of its jaw or headed portion 4 in engagement with the upper and outer surface of the rail base, and its body portion and free end portion resting beneath the bottom 15 of the rail, thus causing said outer end portion to be under a resilient upward tension, then by striking the outer surface of the head or jaw portion with a spike maul or other suitable tool, said jaw portion is 20 driven into its proper position, overlapping one edge of the rail base, such as clearly shown in Fig. 1, while its outer free end portion will rest in close proximity with the opposite edge of the rail base, when by 25 imparting a holding blow, that is of sufficient strength to jar the double leaf spring formation 10, will cause the outer end portion 6 to immediately snap upwardly into 30 tight contact with the edge of the rail base as shown, the anchor being so constructed that said outer end portion will maintain an intense grip or clamping action on the rail, owing to the double leaf spring formation which allows adjustment and always 35 retains an excessive grip to the rail.

An opening 7 is formed through the body portion of the anchor, so that when it is desired to use the anchor at any place, such as on guard rails, frogs, and switches, or 40 where there is any obstruction to prevent the anchor from being driven into its proper position by a pounding blow, a suitable tool may be connected with said opening and with the proper power applied thereto will 45 cause the anchor to spring apart sufficiently to permit the outer end portion 6 to snap into tight contact with the edge of the rail base.

It will be understood that the bar of 50 spring steel from which this anchor is made is heat treated, and while in highly heated condition it is bent upon itself forming the double leaf spring formation 10, the jaw or headed portion 4, the upward extension 6 is 55 formed, and the opening 7 is punched therethrough. The angle of the jaw portion 4 is normally smaller than the corresponding angle of the rail base, hence said jaw is sprung when forced into its proper operative position on the rail base, thus causing 60

the said jaw to co-act with the double leaf spring formation to maintain an intense clamping action thereon, while the terminal of the leaf spring portion serves as a reinforcement of the V-shaped portion, which 70 is adapted to receive a blow for the final clamping action of the outer end of the anchor, and at the same time furnishes additional bearing surface for the anchor against the railroad tie. 75

It is well known that many rail anchors become loose after installation due to corrosion. However, in this particular construction there is always sufficient resiliency to compensate for such corrosion thereby insuring greater longevity. 80

Owing to the construction of this particular type of anchor it will be readily evident that the greater the tendency of the track rail to creep, the more intense will be the 85 gripping action of this anchor to prevent the creeping, thereby insuring a practical and effective anti-creeper.

Having thus described our invention what we claim and desire to secure by Letters Patent is:—

1. A single piece rail anchor comprising a doubled resilient jaw portion forming an overlapping double leaf spring at one end, an upwardly extended portion at its other 90 end, and a depending intermediate portion.

2. A single piece rail anchor comprising a bar of spring steel formed with an overlapping doubled leaf spring jaw portion at one end, an upward extension at its other end, and a depending intermediate portion adapted to contact with a railway tie. 100

3. A single piece rail anchor comprising a bar of spring steel formed with a double leaf spring, a resilient jaw at one end, an 105 upward extension at its opposite end, and an intermediate depending portion.

4. A rail anchor of the character described, comprising a flat spring steel bar having one end bent upon itself to form a double resilient jaw portion, an upward extension at its other end, and an intermediate depending portion. 110

5. A rail anchor of the character described, comprising a flat spring steel bar having one 115 end doubled over to form a double resilient jaw portion, an upward extension at its other end, and a V-shaped intermediate depending portion.

6. A rail anchor of the character described, comprising a doubled resilient jaw portion at one end, an upward extension at its other end, and an intermediate depending V-shaped portion. 120

7. An anti-creeper of the character described, comprising a flat steel spring bar having one end bent to form a double resilient jaw portion, an upward extension at its other end, and an intermediate depending V-shaped portion. 125

8. An anti-creeper of the character described, comprising a flat steel spring bar having one end bent upon itself to form a double resilient jaw portion, a double leaf 5 spring formation, an upward extension at its other end, and an intermediate depending portion.

9. An anti-creeper of the character described, comprising a flat steel spring bar 10 having one end bent upon itself to form a doubled jaw portion, an intermediate double leaf spring formation, an upward extension at its other end, and an intermediate V-shaped depending portion.

15 10. A rail anchor of the character de-

scribed, comprising a flat steel spring bar having one end doubled to form a jaw portion, a double leaf spring formation, an upward extension at its other end, and a depending intermediate portion.

20 11. A rail anchor of the character described, comprising a flat steel spring bar having one end bent upon itself to form a doubled jaw portion, a double leaf spring formation, an upward extension at its other end, and a depending V-shaped intermediate portion with an opening formed through its body portion for the purposes set forth.
